REAR FLOOR MAT FOR AUTOMOBILES, AND THE LIKE

William C. Gerber, 659 W. Main St., Dalton, Ohio

Filed Feb. 23, 1962, Ser. No. 68,921

Term of patent 14 years

(Cl. D9—6)

FIG. 1

FIG. 2

FIG. 1 is a plan view of a rear floor mat for automobiles and the like embodying my novel design.

FIG. 2 is a fragmentary enlargement of a corner of FIG. 1.

FIG. 3 is a fragmentary top perspective view thereof.

FIG. 4 is an enlarged outline sectional view thereof taken on line 4—4 of FIG. 1.

FIG. 5 is an enlarged outline sectional view thereof taken on line 5—5 of FIG. 1.

FIG. 6 is an enlarged outline sectional view thereof taken on line 6—6 of FIG. 1.

The bottom of the mat is flat and plain.

I claim:

The ornamental design for a rear floor mat for automobiles and the like, substantially as shown and described.
